(57) **CLAIM**

The ornamental design for a grabber assembly, as shown and
described.

DESCRIPTION

FIG. 1 is a perspective view of a grabber assembly;
FIG. 2 is a top plan view of the grabber assembly;
FIG. 3 is a rear elevation view of the grabber assembly;
FIG. 4 is a right side elevation view of the grabber assembly;
FIG. 5 is a left side elevation view of the grabber assembly;
FIG. 6 is a bottom plan view of the grabber assembly;
FIG. 7 is a front elevation view of the grabber assembly;
FIG. 8 is a perspective view of the left arm of the grabber
assembly of FIG. 1;
FIG. 9 is a top plan view of the arm of FIG. 8;
FIG. 10 is a right side elevation view of the arm of FIG. 8;
FIG. 11 is a left side elevation view of the arm of FIG. 8;
FIG. 12 is a bottom plan view of the arm of FIG. 8;
FIG. 13 is a front elevation view of the arm of FIG. 8;
FIG. 14 is a rear elevation view of the arm of FIG. 8;
FIG. 15 is a perspective view of the right arm of the grabber
assembly of FIG. 1;
FIG. 16 is a top plan view of the arm of FIG. 15;
FIG. 17 is a left side elevation view of the arm of FIG. 15;
FIG. 18 is a right side elevation view of the arm of FIG. 15;
FIG. 19 is a bottom plan view of the arm of FIG. 15;
FIG. 20 is a rear elevation view of the arm of FIG. 15; and,
FIG. 21 is a front elevation view of the arm of FIG. 15.
